CORN SHOCKER ATTACHMENT FOR
BINDERS

Marvin L. Ludwig, Dola, Ohio

Application November 26, 1937, Serial No. 176,752

11 Claims. (Cl. 56—411)

This invention relates to a shocker attachment for a corn binder, the general object of the invention being to provide means for forming the bundles coming from the binder into a shock, in such a manner that a firmer shock is produced than the ones made by hand and the stalks are not twisted and which forms a shock which will prevent the corn from molding and enables the corn to be easily husked, with means whereby the shock can be placed in upright position on the ground or can be placed on its side in a wagon so that it can be hauled to the ensilage cutter or to a place of storage.

Another object of the invention is to so construct and arrange the parts that they can be adjusted to make the shock of different numbers of bundles and to actuate the movable parts of the shocker from the binder.

This invention also consists in certain other features of construction and in the combination and arrangement of the several parts to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

30 Figure 1 is a view looking toward the rear of the invention.

Figure 2 is a top plan view thereof.

Figure 3 is a top plan view with the turntable or platform and the upright members removed.

35 Figure 4 is a section on the line 4—4 of Figure 3.

Figure 5 is a section on the line 5—5 of Figure 3.

40 Figure 6 is an elevation of the conveying means for conveying the bundles from the binder up to the turntable or platform of the shocker.

Figure 7 is a section on the line 7—7 of Figure 2.

45 Figure 8 is a section on the line 8—8 of Figure 2.

Figure 9 is a side view of one of the links shown in Figure 7.

Figure 10 is an edge view of said link.

50 Figure 11 is a detail view partly in section showing how the screw shaft in a tubular upright is connected with the lower link of Figure 7.

Figure 12 is a view partly in section and partly in elevation of one of the drive shafts for actuating the pinion of Figure 8.

Figure 13 is a vertical longitudinal sectional view showing the means actuated from the bundle kick off of the binder for placing the drive means of the turntable in operative position.

Figure 14 is a section on line 14—14 of Figure 13.

Figure 15 is a view of one of the dog release levers of Figure 13.

Figure 16 is a section on the line 16—16 of Figure 2.

Figure 17 is a section on the line 17—17 of Figure 16.

Figure 18 is a vertical sectional view through the outer end of the track member shown in Figure 16, this view showing how the worm shaft is supported in the end of the track member.

Figure 19 is a section on the line 19—19 of Figure 16.

Figure 20 is a view partly in section and partly in elevation of the center telescopic post.

Figure 21 is a section on the line 21—21 of Figure 20.

Figure 22 is a fragmentary interior view of the lower section of the post and showing the slot through which one of the arms passes and the ears between which said arm is pivoted.

Figure 23 is a section on the line 23—23 of Figure 20.

Figure 24 is an edge view of the cross bar which connects the upper ends of the linkage shown in Figure 7 together.

Figure 25 is a top plan view of the upper disk member for actuating the upper arms of the center post assembly with a part of the post in section and the arms shown in dotted lines.

Figure 26 is a top plan view of the central portion of the cross member shown in Figure 24 and showing the latch means engaging the flange at the top of the center post.

Figure 27 is a section on the line 27—27 of Figure 28.

Figure 28 is a view of the turntable taken from below.

In these drawings the letter A indicates a horizontally arranged supporting frame which includes the rear track forming member 1, the front track forming member 2 and a third track forming member 3 spaced in front of the member 2 and connected therewith by the parts 4. The three track forming members are of substantially channel-shape in cross section with inwardly extending top flanges and they extend transversely of the direction of travel of the frame and they project from the left hand end of the major portion of the frame. The frame is supported by the

- front and rear wheels 5, the front ones being of castor type so that the shocker can readily follow the binder, to which it is suitably connected at the rear end of the binder, a portion of the binder being shown at B in Figure 2 in dotted lines, the binder including the rotary member b which operates means for kicking off the bundles of corn at the rear end of the binder in the usual or any well known manner.
- 5 10 A circular platform or turntable 6 of substantially saucer-shape as shown in Figure 27 has a centrally arranged circular stud 7 depending therefrom for operating in a bearing member 8 carried by the central part of the frame A, as shown in Figure 3. The flat under portions of the periphery of the turntable engage the rollers 9, one of which is shown in Figure 5 and which are supported in suitable channel-shaped bearings 10 carried by the frame. An annular rack 11, 15 shown in Figures 27 and 28 depends from the under portion of the turntable adjacent the said flat part and this rack is engaged by a gear 12 rotatably arranged on a shaft 13, see Figure 4, which is journaled in the front part of the frame 20 and has its front end connected by a universal joint 14 with a shaft 15 driven from a part of the binder B. The gear 12 is formed with the clutch teeth 16 for engagement by the teeth 17 on a clutch member 18 which is slidably arranged on 25 the rear end of the shaft 13 and is normally held in inoperative position by a spring 19 which is located between the clutch member and the gear, as shown in Figure 4. An annular sectional flange 20 depends from the turntable, the flange having 30 its sections spaced apart to provide the openings 20' between the sections, as shown in Figure 28, the openings being arranged a quarter turn from each other. These openings will each receive a portion of the clutch member 18 when the same 35 has been projected by the spring 19 but when the clutch member has been pushed in, by means to be described, and the turntable is turned a section of the flange 20 will hold the clutch member in retracted position with its clutch teeth 17 in engagement with the teeth 16 of the gear 12. As the 40 clutch member is keyed to the shaft as shown at 18' in Figure 4, this will cause the gear 12 to turn with the shaft 13 which results in rotary movement of the turntable.
- 45 50 A vertically arranged circular member 22 is supported by the uprights 23 from the frame A, in slightly spaced relation to the periphery of the turntable.
- The means for moving the clutch member 18 in- 55 to engagement with the gear 12 and out of an opening 20' are shown in details in Figures 13 and 14. Such means includes a channel-shaped supporting member which includes the central part 24, the front part 24' and the rear part 24'', 60 the parts 24' and 24'' having their ends extending into the ends of the central part and welded or otherwise fastened thereto. A dog carrying channel-shaped member 25 is slidably arranged in the space formed between the inner ends of 65 the parts 24' and 24'' and a rack member 26 is slidably arranged in the space formed by the members 25, 24' and 24''. This rack member is of inverted channel shape as shown in Figure 14 and has the downwardly and forwardly sloping 70 teeth 27 in its top which are adapted to be engaged by the holding dog 28 pivoted between the uprights or ears 29 carried by the upper part of the front end of the member 24, this dog acting to prevent retrograde movement of the rack member 75 26 by the spring 30 which has one end connected with the rear end of the rack member and its other end to a projection 31 at the rear end of the member 24'. A second dog 32 is pivoted between the uprights or ears 33 carried by the member 25, see Figure 14, this dog engaging a tooth 5 of the rack member 26 so that when the member 25 moves forwardly the dog will impart forward movement to the rack member 26. The member 25 is moved forwardly by a cable or link 34 which is connected with the member b of the binding B 10 so that every time this member b operates to discharge a bundle from the binder the member 34 pulls the member 25 forwardly which results in the dog 32 moving the rack member 26 forwardly a distance equal to the distance between a pair 15 of the teeth 27. Then the cable 34 is slackened and a spring 35 returns the member 25 to its neutral position which engages the dog 32 in another tooth 27 while the dog 28 engaging a tooth 27 prevents retrograde movement of the rack 20 member 26. The spring 35 is connected to a bracket 36 fastened to the member 35 and to a bracket 37 connected to the rear end of the member 24''. Figure 2 shows the connection of the cable 34 with the member b. Thus every time a 25 bundle of corn is discharged from the binder upon the turntable of the shocker the rack member 26 is moved forward until a certain number of bundles are placed on the turntable when the front end of the member 26 will strike the clutch 30 member 18, see Figure 4, so as to push the member 18 into engagement with the gear 12 which will connect the gear with the shaft 13 so that the turntable is rotated which will cause a segment of the flange 20 to engage the member 18 to hold 35 the clutch member in operated position. The turntable will continue to move until the next opening 20' in the flange 20 comes opposite the clutch member 18 and then the spring 19 will push the member 18 into the opening and thus 40 disconnect the gear 12 from the shaft 13 and the turntable will come to rest.
- Soon after the turntable starts to rotate a pair of cams 38 on the bottom of the turntable will engage the dogs 28 and 32 so as to release the 45 same from the teeth 27 of the rack member 26 and this will enable the spring 30 to return the rack member to its starting point ready to be again moved forwardly step by step by the bundle discharge means of the binder so that the rack 50 member 26 is automatically returned to its starting point each time the turntable starts to move, which of course, moves another part of the turntable in position for receiving the bundles coming from the binder. As shown in Figure 28 the pairs 55 of cams 38 are arranged adjacent the openings 20'.
- Means are also provided whereby the dogs 28 and 32 can be released by hand by an operator on the binder pulling upon the cable or connection 60 40, the rear end of which is connected to an ear 41 on a dog releasing lever 42 which has a horizontal part extending under the dog 28. The lower end of this lever 42 is connected by a bar 43 to the lower end of a releasing lever 44 which 65 extends under the dog 32. As shown in Figure 4 each releasing lever is pivoted in a bearing 45 attached to the supporting member 24 with an end part depending from the bearing and these end parts are connected together by the bar 43 so that 70 the levers will operate in unison. Thus whenever the operator wishes to release the dogs to permit the member 26 to return to its starting point all he has to do is to pull upon the member 40 which will cause the levers 42 and 44 to raise 75.

the dogs 28 and 32 to releasing position and then the spring 30 will pull the member 26 back to its starting point.

In order to permit the operator to adjust the member 26 relative to its movement, so that different numbers of bundles can be placed on each quarter of the turntable a member 46 is slidably arranged in the member 24' and acts as a stop for the rear movement of the member 26. A part 47 is connected with the member 46 and passes through a slot 48 in the member 24' and a rod 49 has one end connected with the member 47 and its other end is located at a point on the binder where it can be manipulated by the operator so that he can adjust the member 46 to stop the rear movement of the member 26 at any desired point so that it will begin its forward movement from any desired tooth 27. For instance, if eight bundles are to be placed on each quarter of the turntable the stop 46 would be in its rearmost position so that the member 26 can move rearwardly to a point which will enable the dog 32 to engage eight teeth 27 on the member 26 which will result in eight bundles being placed on each quarter of the platform before the platform or turntable is moved. If a less number of bundles are to be placed on each quarter of the turntable then the stop member 46 is moved forwardly so as to limit the rear movement of the member 26 and then the dog 32 will only engage a certain number of teeth so that the member 26 will push the clutch member 18 into engagement with the dog 12 when a less number of bundles is placed on the platform. This enables the operator to make the shocks of different number of bundles. As shown in Figure 3 the supporting member composed of the parts 24, 24' and 24'' is supported on portions of the frame A.

A small platform 50 receives the bundles from the binder and conveying means move the bundles across this small platform and deposits them on the turntable. The conveying means comprises a vertical frame 51, see Figures 2 and 6 supported on one end of the platform 50, the vertically arranged rollers 52 carried by the frame and over which a belt 53 passes, the belt carrying the horizontal arms 54 for pushing the bundles across the platform 50 and over a top portion of the member 22, upon the turntable. One of the rollers 52 has attached thereto a pinion 55 which is located under the small platform 50 and this pinion is engaged by a pinion 56 on a stub shaft journaled in a bearing 57 attached to the underside of the platform 50, the shaft having a beveled gear 58 at its lower end for engagement with a beveled gear 59 on the shaft 13, see Figure 3. Thus the shaft 13 will rotate the conveying means for pushing the bundles from the binder over the platform 50 upon the turntable. The platform 50 is also formed with the legs 60 which carry the wheels 61 at their lower ends, said wheels operating in the track members 2 and 3.

Wheel carriages 62 operate in the track members 1 and 2 and each carriage has attached to one end a tubular post or upright 63 which slopes upwardly and toward the left hand end of the shocker when viewed from the rear. A brace upright 64 rises from each carriage and is fastened to an upper portion of each post or upright 63 as shown in Figure 1. Each carriage is, of course, equipped with the wheels 65. A hook member 66, see Figure 6, is carried by the small platform 50 to engage the front upright assembly 63 and 64 so that the platform 50 and the parts carried thereby will move along the track members 2 and 3.

with said posts or upright assembly. This hook member will hold the platform 50 firmly in position with the beveled gear 58 meshing with the gear 59 when the parts are in neutral or retracted position.

A worm or screw-threaded shaft 67 is rotatably arranged in each of the track members 1 and 2 and passes through a threaded bore in each carriage 62. On the right hand end of each shaft 67 as viewed from the rear of the shocker is a beveled gear 68, each of which is adapted to engage with either one of a pair of beveled gears 69 connected together and slidably arranged on a shaft 70 journaled at the right hand end of the frame as shown at 71. This shaft 70 is driven from the main shaft 13 by the chain and sprockets shown generally at 72 in Figures 2 and 3. Each pair of gears 69 is keyed to the shaft 70 for sliding movement and the two pairs are operated in unison from the binder by the rod 73 leading from the binder and connected to the levers 74 which are pivoted to the frame A and suitably engage portions of the connected gears 69, as shown more particularly in Figure 2. Thus by manipulating the rod 73 the two pairs of gears 69 can be placed in a neutral position out of engagement with the gears 68 or either gear 69 of the pairs can be placed in mesh with the gears 68 so as to drive the shafts 67 in one direction or the other so as to move the carriages 62 in either direction along the track members 1 and 2 and, as before stated, during this movement the small platform 50 with the conveying means thereon will be moved with the upright or post assemblies 63 and 64.

A flexible shaft 75 is slidably arranged in the upper portion of each upright or post 63, see Figure 7, and is composed of a plurality of flat links 76, the lower link having sliding movement in the post 63 which is of non-circular shape in cross section to prevent turning movement of the links therein. The links are pivotally connected together as shown at 77 and each link has one end reduced as at 78 to fit between the ears 79 of the next link, the pivot pin passing through these parts 78 and 79 as shown. Interengaging shoulders 80 and 81 are formed on the ends of the links in such a manner that the links can assume a position where they will all be in alignment when they enter the post 63 but when they extend from the post they will assume a curved position as shown in Figure 7. The flexible shaft 75 composed of the links can be projected from the post 63 or moved into the same through means of a screw shaft 82 rigidly connected at its upper end to the lower end of the lowermost link, as shown at 83 in Figure 11 and said shaft passes through a nut member 84 supported in an intermediate part of each post 63 by the members 85, see Figure 8, and a gear 86 is formed on this member and is engaged by a pinion 87 on a shaft 88 journaled in a part 89 fastened to the post 63, the pinion passing through a slot 90 formed in the post to engage the gear 86. A universal joint 91 connects the shaft 88 with a telescopic shaft 92, shown as composed of the three telescopic sections 92' in Figure 12. This arrangement permits the shaft 92 to be extended and contracted as will be understood. The lower end of each shaft 92 is connected by a universal joint 93 with the shaft of a beveled gear 94, see Figure 1, which is supported at the right hand corner of the frame A, see Figure 2, and each beveled gear 94 is adapted to engage with either one of a pair of connected gears 95 keyed for sliding movement on the shaft 70. These two pairs 75

of gears 95 are adapted to be moved into a neutral position or to have either one placed in mesh with the gear 94, by the operator on the binding machine, through means of a rod 96 connected to the levers 97 which move the gears 95 as the rod 96 is manipulated. Thus the operator on the binder can raise and lower the flexible shafts 75 by manipulating the rod 96 or permit the parts to remain in a position to which they have been 10 adjusted.

A cross bar 98 has spindles 99 at its ends, see Figure 24, which are rotatably arranged in the eyes 100 in the top links 16 of the link arrangements 15. The central portion of this cross member is enlarged and has a centrally arranged opening 101 therein for receiving the upper end of the upper section 102 of a telescopic central post 103, the lower section of which is shown at 104. This central post is detailed in Figures 20 to 22. The upper end of the upper section 102 of the post is provided with a flange 105 which is small enough to pass through the opening 101 of the cross member 98 but said flange is normally held to the cross member by the pair of latch levers 106 pivoted to the cross member as shown at 107, with a spring 108 for holding the arcuate parts of the levers in engagement with the upper section of the post and under the flange 105, as shown in Figure 26. These levers can be moved to releasing position by the cables 109 passing around the pulleys 110, carried by the cross member 98 and connected with the ends of the levers, the cables leading to a suitable point where they can be readily reached and manipulated by an operator. As will be seen by pulling upon the cable the levers will be rocked on their pivots against the action of the spring 108 to move the levers to releasing position so that the central post 103 can be released from the cross member 98 by permitting the flanged upper end of the upper section of the post to pass through the opening 101 of the cross member 98.

The lower section 104 of the post is provided with an enlarged upper end 111 which provides an annular shoulder 112 which is adapted to be engaged by a flange 113 on the lower end of the upper section 102 for preventing the two sections from being pulled apart. The lower end of the lower section is formed with a non-circular bore 114 in its lower end for receiving a non-circular lug 115 extending upwardly from the center of the turntable 6, see Figure 27, so as to cause the post 103 to rotate with the turntable when the lower end of the post is in engagement with the lug 115. The lower section 104 of the post is provided with the upper and lower sets of longitudinally extending grooves 116 in its outer circumference. A slot 117 is formed in the lower section at the upper end of each groove and an internal pair of ears 118 is placed at opposite sides of the slot as shown in Figure 22. An arm 119 is pivoted between said ears and passes through the slot and will occupy a groove when in lowered position. Each arm has a bent part 120 extending inwardly from the pivotal point and a ball 121 is connected with the terminal of said bent part. The balls fit between a pair of disks or plates 122, there being a pair of plates for the balls of the lower set of arms and another pair for the balls of the upper set, the plates of each pair being connected together in spaced relation by the posts 123, as shown in dotted lines in Figure 25, and the two pairs of plates are connected together by the post 124 which has its 75 ends connected with the lower plate of the upper

pair and the top plate of the lower pair as shown in Figure 21. Thus the two pairs of plates will move in unison and when the plates are in raised position the arms will be in a vertical position occupying the grooves 116 but when the plates are in lowered position they will cause the arms 119 to swing outwardly and upwardly into substantially horizontal position. In order to hold the plates in lowered position with the arms extended a latch 125 is pivoted to the top plate, as shown in Figure 25, and has a part passing through a guiding bracket 126 and is adapted to engage a keeper 127 attached to the inner circumference of the post section 104, the top plates each having a slot 128 therein for preventing the keeper from interfering with the movement of the plates. A spring 129 acts to hold the latch in engagement with the keeper and a stop 130 on the top plate limits outward swinging movement of the latch. A cable 131 is connected with the latch and passes through a guide 132 on the top plate and passes upwardly through the upper post section 102 to any suitable point with the outer end of the cable having a ring 133 attached thereto. Thus by pulling upon this cable the latch will be released from the keeper so that the plates can be moved upwardly to swing the arms 119 downwardly into the grooves 116.

A spider 134 is located in the enlarged upper end 111 of the lower section 104 of the post and a swivel 135 is connected to the center of the spider and a cable 136 is connected with the swivel. This cable passes through an eye in the guide member 137 extending upwardly from the cross member 98 and through an eye formed in the outer end of a spring arm 138 extending substantially horizontally from the member 98, see Figure 1, and then the cable extends downwardly to a drum 139 rotatably arranged on the shaft 70 carried by the frame A. Clutch means shown generally at 140 connects the drum with the shaft when in operative position to cause the drum to rotate with the shaft to wind the cable 136 upon the drum. Such clutch means is controlled from the binder by means of a rod 141 pivoted from the binder and connected to a lever 142 pivoted to the frame A and engaging the movable part of the clutch means. A brake 143 is provided for the drum and this brake is controlled from the binder through means of a rod 144 and the bell-crank 145 which is pivoted to the frame A and is connected with the brake band. Thus when the cable is wound on the drum and the clutch means are disengaged the brake will prevent the cable from unwinding from the drum.

A post 146 is carried by the small platform 50, see Figure 2, and one or more spring arms 147 are attached to the post to help guide the bundles as they move across the platform 50 and to prevent the bundles from being pushed or from falling off the right hand end of the platform. A post 148 rises from the frame A at the right hand front corner thereof and carries one or more spring arms 149 which curves over the platform as shown in Figure 2 and tends to limit movement to the right of the bundles moving over the turntable or platform and other spring arms 150 and 151 are carried by a post 152 in the right hand rear corner of the frame, the arm or arms 151 is formed in sections with the sections connected to each other by spring hinges 153 as shown in Figure 2. These arms can be of any suitable construction and arrangement as they simply act to hold the bundles on the turntable 75.

in a compact arrangement and without interfering with the movement of the shock from off the turntable.

As before stated the shocker may be attached to the rear part of the binder in any suitable manner so that the shocker will trail the binder and the various rods and cables can extend to any suitable point on the binder and can be connected to any suitable means for enabling the operator to manipulate them and the shaft 15 can be rotated from any suitable moving part of the binder. The movement of the turntable is fast enough to prevent such movement from interfering with the depositing of the bundles from the binder upon the turntable.

The bundles discharged from the binder by the means operated by the member 5 of the binder are deposited upon the small platform 50 and are moved over the platform and drop over the annular member 22 upon the platform 6 by the fingers 54 of the conveying means which includes the belt 53 driven from the shaft 13 which in turn is driven from the binder through means of the shaft 15. The saucer-shape of the turntable or platform 6 tends to cause the bundles to move toward the center of the turntable, but due to the arms 119 of the center post, the bundles are confined to a quarter area of the turntable, that is, if four sets of the arms 119 are used, as shown in the drawings. It will be understood, however, that as many of these arms 119 can be used as desired or necessary. The spring arm or arms 149 will act to hold the bundles against the arms 119 which extends forwardly with respect to the position of the shocker but the spring arm or arms 149 will move outwardly as the bundles press against the same. The annular member 22 acts to hold the butts of the bundles on the turntable. Each time a bundle is discharged from the binder 10 the rack member 26 is moved forwardly one step and then when the number of bundles for which the stop 46 has been adjusted for, has been placed on said quarter of the turntable the front end of the member 26 will engage the clutch member 18 46 so as to cause the same to connect the gear 12 with the shaft 13 which results in a quarter turn of the turntable to place another quarter in position for receiving the bundles. Soon after the turntable starts to move the cams 38 thereon will 56 release the dogs 28 and 32 so that the rack member 26 is returned to its starting point and then the depositing of other bundles on the second quarter of the turntable will cause the member 26 to move forwardly to again move the clutch member 18 into operative position with the gear 12. As before explained as soon as the turntable moves to a position where an opening 20' of the flange 20 comes opposite the clutch member 18 the spring 19 will project the clutch member into 60 the opening and thus disconnect the gear 12 from the shaft 13 and movement of the turntable will stop, the clutch member 18 acting as a brake or stop for the movement of the turntable. As before explained by adjusting the stop member 46 any required number of bundles can be placed on each section of the turntable and whenever desired the operator can release the dogs 28 and 32 to permit the member 26 to return to its starting point by manipulating the cable 40.

After the turntable has received the predetermined number of bundles a rope or binder is passed around the shock between the upper and lower sets of arms 119. Then the rod 96 is manipulated to cause some of the gears 95 to mesh 75 with the gears 94 of the telescopic shafts 92 to

rotate the nut members 84 in the sloping posts 63 which will move the screw shafts 82 upwardly a sufficient distance to partly project the upper links 76 of the linkage 75. This will cause the cross member 98 to raise the center post 103 5 with the shock thereon a sufficient distance to raise the bottom of the shock above the annular member 22. Then the rod 96 is manipulated to disengage the gears 94 from the gears 95. Then the rod 73 is manipulated to engage the gears 68 with some of the gears 69 which will cause the screw shafts 67 to move the carriages 62 to the left in Figure 2 so that the sloping posts 63 and their braces 64 will move to the left hand end of the tracks 1 and 2 and, of course, carrying with them the cross member 98, the center post 103 and the shock. Then the rod 73 is manipulated to release the gears 68 from the gears 69 and then the gears 94 are again meshed with some of the gears 95 by manipulation of the rod 96 so as to cause the telescopic shafts 92 to again rotate the nut members 84 to cause the screw shafts 82 to project the linkage 75 which will move the member 98 to the dotted line position shown in Figure 2 and thus place the shock beyond the left hand end of the track members 1, 2 and 3. Then the cable 131 is pulled upon to release the latch 125 and when this is done the weight of the shock on the arms 119 will swing said arms downwardly, thus raising the plates or disks 122 and the shock will slide down the center post and rest upon the ground. Then the rod 141 is manipulated to engage the clutch 140 to rotate the drum which causes the cable 136 to move the lower post section 144 into the upper post section 102 35 and pulls the lower section out of the shock. Thus the shock will be deposited upon the ground out of the way of the shocker as the shocker moves forwardly. Then the parts are returned to the original position to receive the bundles for another shock. The spring arm 138 for the cable 136 simply acts to hold the cable out of the way of the shock as it is being formed and when the drum is rotated to wind the cable thereon this arm 138 will swing downwardly, due to its resiliency.

When the shock is to be placed on a wagon the wagon is drawn up alongside the left hand side of the shocker so that as the shock is moved outwardly it will strike the body of the wagon and thus be tilted to lie sidewise on the wagon, during this action the cross member 98 will simply partly rotate in the eyes 100 of the linkage 75. Then in order to pull the center post from the shock the cables 109 are pulled to release the levers 106 55 from the flange 105 of the upper post section 102 and then the center post can be pulled from the shock through the opening 101.

It is thought from the foregoing description that the advantages and novel features of the invention will be readily apparent.

It is to be understood that changes may be made in the construction and in the combination and arrangement of the several parts provided that such changes fall within the scope of the appended claims.

Having described the invention, what is claimed as new is:—

1. A shocker attachment for a binder comprising a frame for attachment to the binder, a turntable on the frame receiving bundles from the binder, means for supporting bundles on different parts of the turntable, means for moving the turntable from the binder, said means including clutch means, means for moving the clutch means 70

- into operative position to partly turn the turntable after a certain number of bundles have been placed on a part of the turntable, means for automatically releasing the clutch means when the turntable has moved to a certain point to bring another part of the turntable to bundle receiving position and means for lifting the shock bodily from the turntable and depositing it to one side of the frame.
5. A shocker attachment for a binder comprising a frame for attachment to the binder, a turntable on the frame receiving bundles from the binder, means for supporting bundles on different parts of the turntable, means controlled by the bundles discharge means of the binder for moving the turntable a partial turn, after a certain number of bundles have been placed on a part of the turntable to bring another part of the turntable into bundle receiving position, means for automatically stopping the turntable after it has completed such partial turning means and means for lifting the shock bodily from the turntable and depositing it to one side of the frame.
10. 2. A shocker attachment for a binder comprising a frame for attachment to the binder, a turntable on the frame receiving bundles from the binder, means for supporting bundles on different parts of the turntable, means controlled by the bundles discharge means of the binder for moving the turntable a partial turn, after a certain number of bundles have been placed on a part of the turntable to bring another part of the turntable into bundle receiving position, means for automatically stopping the turntable after it has completed such partial turning means and means for lifting the shock bodily from the turntable and depositing it to one side of the frame.
15. 3. A shocker attachment for a binder comprising a frame for attachment to the binder, a turntable on the frame receiving bundles from the binder, means for supporting bundles on different parts of the turntable, means controlled by the bundles discharge means on the binder for moving the turntable a partial turn, after a certain number of bundles have been placed on part of the turntable to bring another part of the turntable into bundle receiving position, means for automatically stopping the turntable after it has completed such partial turning, means for lifting the shock bodily from the turntable and depositing it to one side of the frame, and means for regulating the number of bundles placed on said parts of the turntable.
20. 4. A shocker attachment for a binder comprising a frame for attachment to the binder, a turntable on the frame receiving bundles from the binder, means for supporting the bundles on different parts of the turntable, a drive shaft, a gear rotatably arranged thereon, a rack of annular form on the turntable engaged by the gear, a clutch member on the shaft for connecting the gear with the shaft, spring means for normally holding the clutch in inoperative position, a seg- 25
25. mental member for holding the clutch member in operative position and the segments of said member being spaced apart to provide openings into which the spring projects the clutch member when such openings come opposite the clutch member, a member movably supported by the frame, means for moving said member into engagement with the clutch member to move the clutch member into operative position when a certain number of bundles has been deposited on a part of the turntable, whereby the turntable will be given a partial turning movement by the shaft, automatic means for returning the sliding member to its starting point, when the turntable begins to move and means for removing the shock from the turntable.
30. 5. A shocker attachment for a binder comprising a frame for attachment to the binder, a turntable on the frame receiving bundles from the binder, means for supporting the bundles on different parts of the turntable, a drive shaft, a gear rotatably arranged on the shaft, an annular rack on the turntable engaged by the gear, a clutch member on the shaft for connecting the shaft with the gear, spring means for normally holding the clutch member in disengaged posi- 35
35. tion, a segmental flange on the turntable, the segments on which are spaced apart and act to hold the clutch member in engaged position, the spring projecting the clutch member into the openings between the segments when such openings come opposite the clutch member to stop further movement of the turntable, a guide member supported by the frame, a member slidably arranged in the guide member, means actuated by the bundle discharge means of the binder for moving the slide member step by step each time a bundle is discharged from the binder, said slide member engaging the clutch member, after a certain number of bundles have been deposited from the binder onto the turntable, to engage the clutch member with the gear to start movement of the turntable, means for returning the slide member to the starting point after the turntable begins to rotate, an adjustable stop for limiting retrograde movement of the slide member for regulating the number of bundles deposited on each part of the turntable and means for removing the shock from the turntable.
40. 6. A shocker attachment for a binder comprising a frame for attachment to the binder, a turntable on the frame receiving bundles from the binder, means for supporting the bundles on different parts of the turntable, a shaft driven from a part of the binder, a gear rotatably mounted on the shaft, an annular rack on the turntable engaging the gear, a clutch member for connecting the gear with the shaft, spring means for normally holding the clutch member disengaged, means carried by the turntable for holding the clutch engaged while the table makes a partial revolution, after which the means permits the spring to disengage the clutch, a guide carried by the frame, a rack bar slidably arranged in the guide, a dog carrying member slidably arranged in the guide and having a dog thereon for engaging the rack bar, means actuated by the discharge means of the binder for moving the dog carrying member each time a bundle is discharged from the binder by engagement of the dog with the rack teeth, spring means for moving the dog carrying member to its starting point, a holding dog for the rack bar, cam means on the turntable for releasing the dogs after the table starts to move, means for returning the rack bar to its starting point, and means for removing the shock from the turntable.
45. 7. A shocker attachment for a binder comprising a frame for attachment to the binder, a turntable on the frame receiving bundles from the binder, means for supporting the bundles on different parts of the turntable, a shaft driven from a part of the binder, a gear rotatably mounted on the shaft, an annular rack on the turntable engaging the gear, a clutch member for connecting the gear with the shaft, spring means for normally holding the clutch member disengaged, means carried by the turntable for holding the clutch engaged while the table makes a partial revolution, after which the means permits the spring to disengage the clutch, a guide carried by the frame, a rack bar slidably arranged in the guide, a dog carrying member slidably arranged in the guide and having a dog thereon for engaging the rack bar, means actuated by the discharge means of the binder for moving the dog carrying member each time a bundle is discharged from the binder by engagement of the dog with the rack teeth, spring means for moving the dog carrying member to its starting point, a 50
50. holding dog for the rack bar, cam means on the turntable for releasing the dogs after the table starts to move, means for returning the rack bar to its starting point, and means for removing the shock from the turntable.
55. 8. A shocker attachment for a binder comprising a frame for attachment to the binder, a turntable on the frame receiving bundles from the binder, means for supporting the bundles on different parts of the turntable, a shaft driven from a part of the binder, a gear rotatably mounted on the shaft, an annular rack on the turntable engaging the gear, a clutch member for connecting the gear with the shaft, spring means for normally holding the clutch member disengaged, means carried by the turntable for holding the clutch engaged while the table makes a partial revolution, after which the means permits the spring to disengage the clutch, a guide carried by the frame, a rack bar slidably arranged in the guide, a dog carrying member slidably arranged in the guide and having a dog thereon for engaging the rack bar, means actuated by the discharge means of the binder for moving the dog carrying member each time a bundle is discharged from the binder by engagement of the dog with the rack teeth, spring means for moving the dog carrying member to its starting point, a 55
60. holding dog for the rack bar, cam means on the turntable for releasing the dogs after the table starts to move, means for returning the rack bar to its starting point, and means for removing the shock from the turntable.
65. 9. A shocker attachment for a binder comprising a frame for attachment to the binder, a turntable on the frame receiving bundles from the binder, means for supporting the bundles on different parts of the turntable, a drive shaft, a gear rotatably arranged on the shaft, an annular rack on the turntable engaged by the gear, a clutch member on the shaft for connecting the shaft with the gear, spring means for normally holding the clutch member in disengaged posi- 60
70. tion, a segmental flange on the turntable, the segments on which are spaced apart and act to hold the clutch member in engaged position, the spring projecting the clutch member into the openings between the segments when such openings come opposite the clutch member to stop further movement of the turntable, a guide member supported by the frame, a member slidably arranged in the guide member, means actuated by the bundle discharge means of the binder for moving the slide member step by step each time a bundle is discharged from the binder, said slide member engaging the clutch member, after a certain number of bundles have been deposited from the binder onto the turntable, to engage the clutch member with the gear to start movement of the turntable, means for returning the slide member to the starting point after the turntable begins to rotate, an adjustable stop for limiting retrograde movement of the slide member for regulating the number of bundles deposited on each part of the turntable and means for removing the shock from the turntable.
75. 10. A shocker attachment for a binder comprising a frame for attachment to the binder, a turntable on the frame receiving bundles from the binder, means for supporting the bundles on different parts of the turntable, a drive shaft, a gear rotatably arranged on the shaft, an annular rack on the turntable engaged by the gear, a clutch member on the shaft for connecting the shaft with the gear, spring means for normally holding the clutch member in disengaged posi- 75

- holding dog for the rack bar, cam means on the turntable for releasing the dogs after the table starts to move, means for returning the rack bar to its starting point, means for removing the shock from the turntable, manually operated means for releasing the dogs, an adjustable stop in the guide forming the starting point for the rack bar and means for adjusting the stop from the binder to regulate the amount of bundles deposited on each part of the platform.
8. A shocker attachment for a binder comprising a frame for attachment to the binder, a turntable on the frame receiving bundles from the binder, a member surrounding the turntable for holding the butts of the bundles on the turntable, a telescopic post having its lower end removably connected with the center of the turntable and said post rotating with the turntable, arms pivoted to the post, means for normally holding the arms radiating from the post to support bundles on different parts of the turntable, automatic means, controlled by the discharge of the bundles from the binder upon the turntable, for imparting a partial turning movement to the turntable after a certain amount of bundles has been placed on the turntable and between two groups of arms on the post, an upright frame movably supported on the first-mentioned frame, means for detachably connecting the upper end of the post to said frame, means for raising the post to cause the bottom of the shock to clear the member which surrounds the turntable, means for moving the upright frame toward one side of the main frame to move the shock off the turntable, manually operated means for releasing the arm holding means to permit the shock to slide down the post and means for raising the lower section of the telescopic post into the upper section to remove the post from the shock.
9. A shocker attachment for a binder comprising a frame, wheels for supporting the same, means for attaching the frame to the binder, a turntable on the frame, conveying means for conveying the bundles from the binder onto the turntable, means for holding the butts of the bundles on the turntable, a shaft driven from the binder, means actuated from the bundle discharge means of the binder for giving the turntable a partial revolution from the shaft, each time a certain number of bundles has been placed on the turntable, means for regulating the number of bundles placed on each part of the turntable, an upright frame slidably arranged on the wheel supported frame, a cross member at the upper end of said upright frame, a rotary shaft supported by the wheel supported frame, means for driving the same from the first-mentioned shaft, means controlled from the binder for moving the upright frame on the wheel supported frame from the second-mentioned shaft, a telescopic post detachably connected with the cross member, means for removably connecting the lower end of the post to the turntable to cause the post to turn with the turntable, radiating arms carried by the lower section of the telescopic post, said section having grooves therein for receiving the arms when the same are in lowered position, means for pivotally connecting the arms to the said section, means in said section for normally holding the arms in horizontal position, manually operated means for releasing the holding means to permit the arms to move downwardly into the grooves, a cable connected with the lower section of the post, a drum on the second shaft to which the cable is connected, clutch means controlled from the binder connecting the drum with the second shaft to wind the cable on the drum to move the lower section of the post into the upper section of the post, when the arms are occupying the grooves, brake means for the drum, means for controlling the same from the binder, means for extending the upper portions of the upright frame to raise the cross member and the post and means controlled from the binder for actuating the last-mentioned means from the second shaft.
10. In a shocker attachment for a binder comprising a frame for attachment to the binder, a turntable on the frame receiving bundles from the binder, an upright frame slidably arranged on the first-mentioned frame and including posts of tubular construction sloping upwardly toward one side of the first frame, a flexible shaft in each post composed of a plurality of links having shoulders thereon for holding the flexible shaft in an upwardly and outwardly bowed position when the flexible shaft is projected from the tubular post, a cross member having its ends pivoted in the outer ends of the flexible shafts, a center post having its upper end detachably and rotatably supported from the cross member, means for removably connecting the post with the center of the turntable to cause the post to revolve with the table, said post being formed of upper and lower telescopic sections, radiating arms pivoted to the lower section, means in the lower section for holding the arms in either a horizontal position or in a depending vertical position, means for locking said holding means in a position with the arms extending horizontally, manually operated means for releasing the last-mentioned means, a driven shaft, manually controlled means for moving the sliding frame from said shaft, manually controlled means for projecting and retracting the flexible shafts from the said driven shaft, a cable connected with the lower section of the center post, a drum on the driven shaft to which the cable is connected, manually controlled clutch means for connecting the drum with the shaft and manually controlled brake means for the drum.
11. In a shocker attachment for a binder comprising a supporting frame, a shock supporting member on the frame, means for conveying the bundles from the binder onto said member, an upright frame slidably arranged on the supporting frame and movable toward and away from one side thereof, power means for moving said upright frame, telescopic members at the upper end of the upright frame, a cross member carried by said telescopic members, power means for projecting and retracting the telescopic members, means for connecting the cross member with the shock, means for releasing the shock from said member and spring arms for holding the bundles in a shock.

MARVIN L. LUDWIG.
